PNEUMATIC HAMMER

Roy J. Champayne, Rockford, Ill.

Application March 25, 1939, Serial No. 264,067

6 Claims. (Cl. 153—32)

This invention relates to pneumatically actuated hammers of the type used for straightening sheet metal parts such as the fenders, bodies, etc. of automotive vehicles.

The general object is to provide such a hammer which is more powerful and efficient in operation, simpler and less expensive in construction and easier and more convenient to control than prior hammers of the same general character.

A more specific object is to provide for raising of the lower die member to and holding the same in operative position by pneumatic pressure without detracting from the ease of control or the versatility of the hammer.

Another object is to provide for control of the hammer by the operator's thumb while the hammer is gripped by the operator's hand in a convenient position of balance.

A further object is to lubricate the mounting of the lower die member in a novel manner.

Still another object is to provide a novel construction and mounting of the upper die member contributing to the versatility of the hammer.

The invention also resides in the novel manner of coupling the yoke detachably to the pneumatic actuator head and the novel means for closing the upper end of the actuator of the actuator cylinder.

Other objects and advantages of the invention will become apparent from the following detailed description taken in connection with the accompanying drawings, in which

Figure 1 is a perspective view of a pneumatic hammer embodying the novel features of the present invention illustrating the manner of using the hammer in straightening a fender.

Figs. 2, 3, and 4 are side elevational views of the improved hammer equipped with yokes of different shapes and with portions of the yoke shown in section.

Fig. 5 is a fragmentary diametrical cross sectional view of the improved hammer with the central portion of the yoke broken away.

Fig. 6 is a fragmentary perspective view of part of the hammer head.

Fig. 7 is a section taken along the line 7—7 of Fig. 5.

While the invention is susceptible of various modifications and alternative constructions, I have shown in the drawings and will herein describe in detail the preferred embodiment. It is to be understood that I do not thereby intend to limit the invention by such disclosure, but aim to cover all modifications and alternative construc-

tions falling within the spirit and scope of the invention as expressed in the appended claims.

The hammer shown by way of illustration comprises generally a yoke 10, a lower die member 11 mounted on one end of the yoke for vertical movement into engagement with one side of the work piece W to be operated upon and a head 12 detachably mounted on the other end of the yoke and having self-contained therein an upper die member 13, a pneumatic actuator therefor, a connection with a source of air pressure and a manually operable control valve.

To adapt the hammer for operation on various types of sheet metal pieces or different locations on a vehicle body, various sizes and shapes of yokes may be employed as shown in Figs. 2, 3, and 4. Each of these yokes is substantially G-shaped, being bent intermediate its ends to form generally parallel opposite end portions or arms 14 and 15. The arm 14 is substantially straight clear to its end while the arm 15 preferably is bent as indicated at 16 near its end to form a short end 17 the axis of which is disposed at right angles to the axis of the arm 14 and intersects the latter axis a short distance beyond the end of the arm 14. By virtue of the bend 16, the yoke is of greater effective width adjacent its ends, thereby contributing to the versatility of application of the hammer to various kinds of work.

In the present instance, the lower die member 13 is raised into contact with the work by air pressure and constitutes a yieldable backing for supporting the work from its under side when each blow is struck by the upper die member. For this purpose, a sleeve 18 screw threaded onto the end 17 cooperates with the latter to form a cylinder 19 in which a piston 20 reciprocates freely. A leather washer 21 is attached to the lower end of the piston to minimize leakage and to facilitate lubrication of the piston in a manner to be described later.

The piston projects from the cylinder and its reduced upper end 22 is received in a socket 23 on the under side of the die member 11, the two being held together frictionally by an expandable ring 24 encircling a groove in the end 22. The die member may be detached from the piston and replaced by one having an upper surface of a contour best suited to the work piece to be operated upon.

The invention contemplates utilizing the yoke 10 to perform the additional function of conducting air under pressure to the lower end of the cylinder 19 so as to maintain the lower die raised

as shown in Fig. 5 during operation of the tool. To this end, the yoke comprises a single piece of seamless steel tubing and, as will appear later, air is admitted to the end 14 of the tube and conducted to the cylinder 19 through the entire length of the tube. The yoke may thus be constructed as a single integral piece without joints or holes therein for admitting the compressed air.

The head 12 is a generally T-shaped tubular casting and comprises a tube 26 and a tubular extension 27 internally machined to receive the end of the straight yoke arm 14, the end abutting against a gasket 28 backed by a shoulder 29. The yoke and head are fastened together in a novel manner which permits of ready disconnection of the two to interchange yokes or of swiveling of the head about the yoke in applying the tool to certain kinds of work while at the same time insuring against breakage or loosening of the parts under the severe vibration to which the coupling is subjected in service operation. For this purpose, a longitudinally extending slot 30 is formed in the extension 27 and is adapted to receive the squared head 31 of a set screw 32 threaded into the yoke arm 14 at a point spaced from its end. Ears 33 cast on the extension on opposite sides of the slot 30 are apertured to receive a bolt 34 which is transversely milled to form a slot 35 that registers with the slot 30 when the bolt is fully entered through the ears and turned to a predetermined angular position.

The arrangement is such that when the yoke end 14 is fully entered and abutting against the gasket 28, the lug 31 will be disposed beyond the axis of the bolt as shown in Fig. 5. By means of a wrench applied to its head, the bolt is turned in a counter-clockwise direction so that the edge 36, acting on the lug 31, forces the yoke arm firmly against the gasket. With the parts thus held, a wing nut 37 is tightened thereby contracting the extension 27 around the yoke arm and clamping the two firmly together. After loosening the nut, the head 12 may be slipped entirely off from the yoke and applied to another yoke. Or, the head may be slid off far enough to permit the head to swivel about the yoke arm 14.

The lower end of the head tube 26 is machined externally as indicated at 42 to snugly receive a flange 38 on the upper die member 13 which therefore is of cup shape. The cup may be retained on the tube frictionally as by means of a contractible ring 39 seated in a groove 40 around the flange and having a part projecting through an arcuate slot 41 and bearing against one side of the surface 42.

The tube 26 is bored to form two cylinders 43 and 44 in which reciprocates a plunger 45 having two spaced pistons 46 and 47 sliding in the cylinders 43 and 44. The lower end 48 of the plunger extends beyond the piston 46 and has a hardened head 49 which strikes the upper die member as shown in full lines in Fig. 5 when the plunger is projected downwardly. This head constitutes an auxiliary die member of smaller size than the main die member 13 and will be projected from the tube 26 and operate directly on the work when the main die cup is removed.

The other end of the plunger 45 has an axial bore 50 communicating with radial passages 51 which terminate in an annular groove 52 on the piston 47. The groove is adapted to register with a wider internal groove 53 in the cylinder

44 above which an exhaust port 54 is cut through the casting.

The outer end of the cylinder 44 is closed by means including a disk 55 pressed into the counterbored end of the cylinder below a groove 56 in which a ring 57 is expanded. A cap 58 is clamped against the end of the tube by a screw 59 extending through the cap and threading into the disk 55 to draw the latter against the ring 57. A fluid tight closure is thus provided which is not subject to loosening or breakage of the parts under the severe vibration encountered in service use of the hammer.

With the plunger lowered as shown in full lines, air under pressure is admitted through a passage 60 to the space between the pistons 46 and 47. Owing to the larger size of the piston 47, the plunger is raised. After the port 54 has been covered and when the piston 47 passes the groove 53, the compressed air flows through the groove 52, the passages 51 and the bore 50 into the space above the piston. Here the pressure builds up rapidly, first cushioning and arresting the upward movement of the plunger without the latter contacting the disk 55. Then, the compressed air, acting on the upper end of the piston 47, projects the plunger downwardly. This continues until the plunger reaches the position shown in full lines at which time the groove 53 is covered and the port 54 is uncovered by the piston 47. As a result, the plunger is reciprocated extremely rapidly imparting a sharp impulse to the die member 13 on each downward stroke.

A hose 60 leading from a source of compressed air is attached to a fitting 61 threaded into a boss 62 on the upper side of the tubular extension 27 beyond the end of the yoke and closely adjacent the tube 26. Between the fitting and the cylinder 44, the tubular extension 27 is formed with a transverse bore 63 which intersects the passage 60 perpendicular to the plane of the yoke 10. A rotary valve member 64 in the form of a cylindrical pin projects through the bore 63 and has a diametrical passage 65 therethrough. With the pin positioned as shown in Fig. 5, the valve is closed. When the member 64 is turned through a small angle in a clockwise direction, the passage 65 is brought into register with the passage 60 permitting air to flow from the hose into the cylinders 43 and 44 and also through a passage 66 into the end 14 of the yoke. The extent of such angular movement determines the amount of air admitted and therefore the speed of the pneumatic actuator.

The valve is arranged to be actuated and the degree of opening controlled variably and accurately by manipulating the thumb of one of the operator's hands while the hammer is gripped or held by such hand at a convenient and natural point of balance. For this purpose, a generally L-shaped actuator arm 67 is extended radially into and rigidly attached to the projecting end of the valve member 64, preferably on the left side of the hammer. The other or free end of the arm bends upwardly and carries a knob 68 by which the arm may be depressed by pressure applied to the top of the knob. The arm swings between limit valve open and closed positions against lugs 69 and 70 cast on the side of the extension 27. A torsion spring 71 coiled about the projecting end of the valve pin 64 inside of the arm 67 bears at one end against a lug 72 on the extension

27 and has its other end hooked around the arm 67. The spring thus urges the arm upwardly toward closed position (Fig. 6) against the stop 70.

Preferably, the arrangement of the parts is such that in the closed position of the valve, the knob 68 is disposed above the tubular extension 27 but within convenient reach of the thumb of either of the operator's hands. Thus, when the operator is gripping the yoke with his right hand at the natural place of balance of the hammer, that is, adjacent the extension 27 as shown in Fig. 1, the right thumb is free to depress the knob 68 or allow it to rise under the action of the spring 71. All positions of the actuating arm down to the fully open position shown in dotted outline in Fig. 5 may be maintained conveniently by the operator's thumb without in any way disturbing the operator's grip on the tool. As a result, the valve can be moved to regulate the air flow while the tool is being moved back and forth across the work as is the practice in straightening a work piece.

It is sometimes desirable to support the hammer in a vise and move a work piece back and forth between the die members with the pneumatic actuator operating. To do this, it is only necessary to disengage the spring 71 from the lug 72. Then, the arm 67 will, with the yoke portion 14 disposed generally horizontally, fall by gravity to open position, thereby causing normal actuation of the die members.

Provision is made for causing the lower die member 11 to bound away from the under side of the work under each impact of the plunger 45 of the upper die member 13, thereby relieving the frictional drag of the die members on the work so as to permit the hammer to be moved easily back and forth across the work. At the same time, this bounding movement is controlled in magnitude and so synchronized with the movements of the plunger that the lower die member will always be forced back against the work before the next blow is struck by the plunger. This important action is obtained by properly proportioning the relative weights of the pressure actuated parts as well as the effective pressure areas of the piston 20 and the plunger 45. In the present instance, the piston 20 is approximately one inch in diameter while the diameters of the pistons 46 and 47 are one and one-quarter and one and three-eighths inches respectively. Thus, during the retracting or upward stroke of the plunger, the piston 20 has a substantially greater effective pressure area than the plunger 45, the pressure area of the latter being determined by the differences in the diameters of the pistons 46 and 47. On the down or active stroke, when the air pressure is exerted on the upper end of the plunger, the effective pressure area is greater than that of the piston 20. The cup 13 and plunger 45 weigh six and eleven ounces respectively while the piston 20 and the lower die member 11 carried thereby weigh approximately one pound. The parts thus proportioned will, under air pressure of sixty-five pounds per square inch or over, operate in the desired manner, the lower die member rebounding from the work a distance of approximately one-sixty-fourth of an inch. In addition, the return of the lower die member into contact with the work and the striking of the next blow by the plunger 45 are so timed that while the lower die member is always positioned

against the work so as to back the latter when a blow is struck, the period of contact is relatively short. As a result, the hammer exerts very little frictional drag on the work and the operator may easily move the tool across the work while gripping it with one hand only as shown in Fig. 1. Such accurate timing of the active movements of the plunger and the bounding of the lower die member avoids any possibility of a blow being struck when the work is not backed by the lower die and thus prevents denting of the work which might otherwise occur.

By interconnecting the cylinders 19, 43, and 44 through the tubular yoke and by making the effective pressure area of the piston 20 greater than that of the plunger 45 on the up or inactive stroke of the latter, the lower die will always be raised into contact with the work before the plunger is actuated to strike a blow. That is to say, the piston 20 will be raised under a pressure in the yoke lower than that required to raise the plunger due to the difference in the effective areas of the pistons 46 and 47. As a result, the initial plunger movement will occur only after a pressure build up in the yoke and the cylinders 19, 43, and 44 following raising of the lower die.

Preparatory to straightening a piece of sheet metal such for example as the fender of a vehicle, the operator usually grips the hammer with one or both hands. As illustrated in Fig. 1, the fingers of one hand are extended around the underside of the yoke arm 14 adjacent the tubular extension 27 but leaving the thumb of the latter hand free to depress the knob 68 of the valve arm. With the valve closed, the lower die will be separated by gravity from the upper die as shown in dotted outline in Fig. 5. The work may easily be brought endwise in between the dies. When the latter are located on opposite sides of the portion of the work to be straightened, the arm 67 is depressed and the valve opened to admit air simultaneously to the tube 10 and the cylinders 19, 43, and 44. This first raises the piston 20 to force the lower die against the work and the latter against the upper die 13. Then, the pressure builds up sufficiently to actuate the plunger 45. The pressure is first effective on the under side of the piston 47 to raise the plunger as previously described. Then, after the piston 47 uncovers the groove 53, the full pressure is applied to the upper end of this piston and the plunger is projected downwardly to strike a sharp blow on the upper die member. The blow is transmitted to the work and the lower die member without noticeable movement of the cup 13. The plunger reciprocates extremely rapidly and any irregularities in the work are hammered out effectually by the substantially flat surface of one die coacting with the curved surface of the other. Different areas of the work are covered by moving the dies across the work usually by sidewise motion of the yoke. This may be accomplished easily and even by one hand only because of the small friction drag which, as previously described, results from limiting the downward bounding of the lower die and properly timing its rebound. So rapid and effective is the hammering action that badly bent metal of heavy gage such as is used in truck fenders may be smoothed out quickly without appreciable marring of the enameled surface.

To operate on unusually heavy stock, it is sometimes desirable to remove the cup 38 and

permit the hardened head 49 to constitute the upper die member and act directly on the work. The plunger blow thus acts over a smaller work area and is accordingly more effective.

Lubrication of the lower piston 20 may be effected simply and conveniently by removing the piston from the cylinder 19 and placing a body of solid lubricant such as grease 75 in the upturned end 17 of the yoke. The vibration to which the hammer is subjected in service operation causes this grease to creep upwardly along the inner wall of the tube into the cylinder 19 and be distributed effectually over the piston walls. This action is aided by bending the lower end of the yoke as described and joining the cylinder 19 and tube so that their inner walls form a substantially continuous surface.

To lubricate the pistons 46 and 47, the die cup 13 is removed and the plunger is permitted to fall below its normal position to one in which the piston 46 is disposed below an oil hole 76 in the tube 26. Lubricating fluid is introduced through this hole and since it comes in between the pistons, both of the latter are lubricated effectually.

I claim as my invention:

1. In a pneumatic hammer of the character described, the combination of a die head, a yoke, and a joint connecting one end of said yoke and said head to prevent loosening of the joint under the vibration encountered in service use of the hammer, said joint comprising a tubular extension on said head and adapted to receive the end of said yoke, said extension being slotted longitudinally at its end, an abutment within said extension for limiting the entry movement of said yoke end, ears on said extension disposed on opposite sides of the slot therein, a clamping bolt extending through said ears and said slot and having a transverse groove therein adapted to register with the said slot in one angular position of the bolt, and a projection on said yoke end adapted to move through said slot and groove and to be engaged by said bolt upon turning of the latter out of alignment with said slot, said bolt when tightened serving to contract said extension about said yoke end and acting on said projection to urge the yoke end against said abutment.

2. In a pneumatic hammer of the character described, the combination of a die head, a yoke, and a joint connecting one end of said yoke and said head to prevent loosening of the joint under the vibration encountered in service use of the hammer, said joint comprising a split tubular extension on said head and adapted to receive the end of said yoke, an abutment within said extension for limiting the entry movement of said yoke end, a projection on said yoke end, and a clamping bolt on said head adapted when turned to engage said projection and urge said yoke end against said abutment and when tightened to contract said extension about said yoke end.

3. In a pneumatic hammer of the character described, the combination of a casing having a cylinder therein open at opposite ends, a piston reciprocable in said cylinder, a die member at 65 one end of said cylinder actuated by said piston,

and means closing the other end of the cylinder comprising a recess in the wall of said cylinder, two coaxially arranged disks, one abutting against the end of said casing and closing said cylinder, the other disk fitting snugly within the cylinder beyond said recess, an expandable member between said disks projecting into said recess, and a screw device connecting said disks and clamping the disks against the casing and said member respectively.

4. In a pneumatic hammer of the character described, the combination of a casing having a cylinder therein open at opposite ends, a piston reciprocable in said cylinder, a die at one end of said cylinder projected therebeyond by said piston, and means closing the other end of the cylinder comprising a member disposed within but removable from said other end and projecting inwardly from the wall of said cylinder, a disk abutting against the end of said casing and closing said cylinder, and means including a screw device acting against said member and clamping said disk against the casing end.

5. A pneumatic hammer having, in combination, a single piece tubular yoke substantially straight at one end, means on the other end of said yoke providing a cylinder communicating with the yoke, a piston reciprocable in said cylinder and supporting a lower die member, an integral T-shaped head casting providing a cylinder alined with said first cylinder and having a tubular projection perpendicular to the second cylinder and partially telescoped onto said straight yoke end, a valve including a rotary element journaled in said projection between said cylinder and said first yoke end, means establishing communication within said head between said valve and both said yoke and said second cylinder, an arm carried by said valve element exteriorly of said head and depressible by the thumb of the operator's hand grasping said projection to support the yoke, a piston reciprocable in said second cylinder, and an upper die member actuated by said last mentioned piston.

6. A pneumatic hammer having, in combination, a single piece tubular yoke substantially straight at one end, means on the other end of said yoke providing a cylinder communicating with the yoke, a piston reciprocable in said cylinder, a lower die member actuated by said piston, a head providing a cylinder alined with said first cylinder and a lateral tubular projection telescoping with said straight yoke end, said head having a fluid supply passage leading thereto, a valve having an element movably mounted on said head and operable to establish communication within said head from said passage to said yoke and to said second cylinder, an arm mounted on said head exteriorly thereof and depressible by the thumb of the operator's hand grasping said projection to support the yoke, said arm being connected to said valve element and operable when depressed to open the valve, a piston reciprocable in said second cylinder, and an upper die member actuated by said last mentioned piston.

ROY J. CHAMPAYNE.
